FEEDING MACHINE FOR ROLLING MILLS

James B. Johnson, Cleveland, Ohio, assignor to
Mary Anita Johnson, Cleveland, Ohio

Application February 14, 1939, Serial No. 256,297

13 Claims. (Cl. 80—26)

This invention relates to article feeding apparatus and is particularly adapted to feeding articles to other mechanisms which perform various operations upon them, such, for instance, as to feeding blanks or billets to rolling mills or the like.

An object of the invention is to provide an improved feeding apparatus which is capable of gripping, holding, and feeding articles into a plurality of working mechanisms successively.

Another object of the invention is to provide an improved feeding apparatus in which the articles may be presented in a different relationship to the successive operating mechanisms.

Another object is to provide an improved feeding apparatus which may be readily arranged to vary the conditions of the articles being handled thereby.

Another object of the invention is to provide an improved feeding apparatus which may be automatically actuated.

Another object is to provide an improved feeding apparatus which will be compact in arrangement.

Another object of the invention is to provide an improved feeding apparatus which will be positive in action.

Another object of the invention is to provide an improved feeding apparatus which will be speedy in operation.

Other objects will hereinafter appear.

The invention will be better understood from the description of one practical embodiment thereof, illustrated in the accompanying drawings, in which, for illustrative purposes a plurality of rolling mills have been shown, these being of the kind which perform successive operations on billets to produce automotive axles or similar articles; in the drawings:

Fig. 1 is a plan view of one embodiment of the invention, showing the article holding and moving carriages in their innermost or starting positions;

Fig. 2 is an end elevational view of a carriage operating unit;

Fig. 3 is an end elevational view of one of the rolling mill units, showing the driving motor and elements of the driving means by which the carriage is operated;

Fig. 4 is a partially elevational and partially sectional view of the feeding mechanism at its loading station;

Fig. 5 is a view similar to Fig. 4, but taken at the first operating or rolling mill station, and showing the carriage at its outermost position;

Fig. 6 is a plan view of Fig. 4, the turn-table being omitted.

Fig. 7 is a front elevation of the cam-ring for controlling the movement of the push-pins of the turn-table,

Fig. 8 is a view of the locking pawl for the rack-bar,

Fig. 9 illustrates the means for releasing the locking pawl,

Fig. 10 is a longitudinal section view of the carriage,

Fig. 11 is a front end view of the head of the carriage,

Fig. 12 is a side view of the carriage sleeve,

Fig. 13 an elevation of the cam for imparting a partial rotation to the carriage head,

Fig. 14 is an end view of the same, and

Fig. 15 is a plan view thereof.

Referring to the drawings, the feeding machine illustrating the invention consists of a spider like base 1 having a center 2 and a plurality of radially extending and equally spaced arms or runners indicated by 3. Fixed in the center 2 of the base is a vertical shaft 4, on which is rotatably mounted a sleeve 5. A suitable ball-bearing unit 6 on the shaft 4 supports the sleeve 5 upon the center 2 of the base. Loosely mounted on the shaft 4 but fixed to the upper end of the sleeve 5 as indicated by screws 7 and therefore rotatable with said sleeve is a push-member or actuator 8 having four radially extending arms as indicated by 9. On the shaft 4 and resting upon the push-member 8 is a ball-bearing unit 10 for supporting a circular turn-table 11.

Arranged around the turn-table 11 and bolted as at 12 to several of the successive runners 3 of the base are a plurality of rolling mills, each indicated as a whole by 13, 14 and 15. Also arranged around the turn-table and bolted to the next preceding and succeeding runners to which the rolling mills are secured, is a carriage operating unit 16 for loading and a similar carriage operating unit 17 for unloading. The rolling mills 13, 14 and 15 are of the back rolling type of ordinary construction, consisting of a pair of housings 18 and 19, in which are supported the segment rolls 20 and 21 having central coacting pass grooves 22 and 23, and driven by gears 24 and 25, to which power is applied.

The turn-table 11 is provided with equally spaced radially extending guide slots indicated by 26 and corresponding in vertical alignment with the pass grooves of the rolls of the mills. Carriages 27 having longitudinally extending bases 28 are slidably mounted in the guide slots

26 of the turn-table 11 and are supported thereon by rollers 29 while retaining rollers 30 engage the underside thereof. The carriages 27 are for the purpose of carrying the billets to and into and out of the rolling mills for the successive operations thereon. For rotating the turn-table 11 in a step-by-step movement and thereby moving the carriages 27 in the same manner to a position opposite each mill in succession, the following described mechanism is provided.

The rolls 20 and 21 of the mills may be driven from any source of power applied to the gears 24 and 25. Supported by the housings 18 and 19 of each mill 13, 14 and 15 below the rolls thereof is a cross-shaft 31, to one outer end of which is fixed a gear 32 meshing with the roll gear 25 and the other outer end thereof a heavy fly-wheel 33. An electric motor 34, preferably fixed to the top of one of the mills, for instance 13, drives the fly-wheel 33 by means of a belt 35. Keyed to the center of the cross-shaft 31 is a worm-wheel 36, which drives a worm 37 of a radially extending main power shaft 38 supported in bearings 39 and 40 bolted to the runner 3 of the base. Fixed to the inner end of the shaft 38 is a bevel gear pinion 41, which drives a large central bevel gear 42, which is adjustably fixed to the sleeve 5 by means of a set-screw 43. Each of the other mills 14 and 15 are driven from the central bevel gear 42 by a radially extending shaft 44, a bevel gear pinion at its inner end, a worm fixed to said shaft driving a worm-wheel of a cross-shaft having a fly-wheel at one end and a gear at the other, all as just described for the first mill. Both the carriage operating unit 16 for loading and the carriage operating unit 17 for unloading are also driven from the central bevel gear 42 and have similar housings to those of the mills, but lower as indicated at 45, for supporting a cross-shaft 46, to which is fixed at its center a worm-wheel 47. Said worm-wheel is driven by a worm 48 fixed to a radially extending shaft 49 supported in bearings 50 and 51 secured to the runners of the base and having at its inner end a bevel pinion 52 in mesh with the bevel gear 42. The periphery of the turn-table may be supported by rollers as at 53 carried by the housings of the mills, or the carriage operating units, or from the runners of the base.

Continuous rotation of the central bevel gear 42 and the sleeve 5 causes step-by-step rotary movement of the turn-table 11 by an arm 9 of the push-member 8 carried by said sleeve engaging push-pins 54 which depend from the turn-table and are arranged in the arc of a circle. The push-pins 54 are pivoted at 55 to lugs 56 of the turn-table so as to swing radially out of the path of the arms 9 of the push-member 8 but be rigid and afford resistance in the rotary direction thereby causing rotation of the turn-table by said push-member. The push-pins 54 are arranged with their centers, indicated by 57, between each radial slot 26 of the turn-table 11 and normally hang vertically. As the turn-table rotates, the push-pins 54 are adapted to be swung upwardly and outwardly by engaging the inclined upper edge 58 of an inturned end 59 of a cam-ring 60 and continuing on the upper edge 61 thereof until its abrupt ending at 62, when the push-pins return to their normal depending positions to be again acted upon by the next arm of the push-member 8. An inturned end 63 of the cam-ring 60 is adapted to serve as a stop against backward rotation of the turn-table.

The carriages 27 are moved outwardly upon the turn-table 11 to feed the billets into the mills and then returned to their original positions by the following described mechanism. Depending 5 from the bottom of the base 28 of each carriage 27 is a stub-pin 64, which is adapted to travel in the space or recess 65 formed by two concentric rings 66 and 67 arranged around the cam-ring 60. The rings 66 and 67 are divided radially into 10 equal sections as indicated by 68, so that their radial centers are in alignment with the vertical centers of the mills 13, 14, 15 and the carriage operating units 16 and 17. Each section of the rings 66 and 67 are held in spaced relation by 15 a pair of straps as at 69, which are fixed at 70 to an inverted yoke 71 having depending sides 72 and 73. The yoke 71 is supported by rollers at 74 carried by the inner faces of the sides thereof and engaging the upper and lower sides 20 of a pair of tracks 75 and 76, which are fixed at one end in the housings of the mills and the carriage operating units, while their other ends terminate in legs as at 77 which are fastened to the runners 3 of the base. One or more of the sections 25 68 may, if desired, be supported in stationary position by legs 78 attached to the arms 3 of the base.

To one of the sides as 72 of each yoke 71 is pivoted as at 79, the inner offset end of a 30 rack-bar 80, the free outer end of which rests upon a suitable cam 81 fixed to the outside of a gear-wheel 82 carried by a stub-shaft 83 extending from the side of the housing of the mill or carriage operating unit and in mesh with the gear 35 32. The cam 81 is adapted to alternately raise the free outer end of the rack-bar 80 to cause its teeth 84 to engage the gear 32 and then to permit same to fall sufficiently that its teeth will clear said gear. A flat spring 85 enclosed in a circular 40 casing 86, which is secured to a bracket 87 fastened to the runner 3, is connected to the outer end of the rack-bar 80 and tends to exert a pulling action thereon. When the teeth 84 of the 45 rack-bar 80 are out of engagement with the gear 32, the spring 85 forces said rack-bar outwardly and moves the yoke 71, the section of rings 68, and consequently the carriage 27 in the same direction, and when the teeth of said rack-bar engage said gear, said rack-bar is forced inwardly 50 by the action of said gear, thereby moving the carriage in that direction. A stop 88 adjustable on the track 75 limits the outward movement of the yoke 71 and the carriage 27.

For the purpose of holding the rack-bar 80 in 55 its inner position and the carriage in the same position, a locking pawl 89 is pivoted at 90 to a bracket 91 secured at 92 to the base of the housing of the mill and rests upon and is adapted to engage the teeth 84 of said rack-bar. In order 60 to lift the locking pawl 89 out of engagement with the teeth 84 of the rack-bar to permit the spring 85 to act thereon to move the carriage 27 outwardly at the proper time, the following means is employed. On a vertical rod 93 fixed in a boss 94 65 of the housing is slidably mounted a tube 95 having a bottom flange 96. A head 97 is adjustably fixed to the tube 95 by means of a set-screw 98 and has a lateral finger 99 which passes loosely through an opening 100 of a lug 101 of the locking pawl 89. The tube 95 is lifted and consequently the locking pawl 89 by means of a lever 102, which is pivoted at 103 to the base of the housing. The lever 102 is adapted to be actuated by a suitable cam 104, which is fixed to the radial 70 shaft for engaging its inner free end while its 75

outer forked end 105 passes under the flange 96 of the tube 95.

The carriages 27 are adapted to automatically grab and grip the billets and also partially rotate same for each pass through the rolls, and the mechanism for accomplishing same will now be described. The base 28 of each carriage supports a pair of spaced aligning end bearings 106 and 107, in which is rotatably and slidably mounted a longitudinally extending shaft 108 having at its inner end a hub 109 carrying radial arms 110. The outer end portion of the shaft 108 is fixed to a longitudinal head 111 slidably in a sleeve 112 and having an inner reduced end 113 rotatably and slidably supporting said head in the bearing 106. The shaft 108 and the head 111 thereof are slidable in the sleeve 112 and said shaft is rotatable with said sleeve by means of a pair of longitudinal slots as 114 in said sleeve, in which pins 115 fixed in the head 111 slide. Clamping jaws 116 are fixed to the outer projecting ends of right angle lever-arms 117 pivoted at 118 in recesses 119 of the head 111 while the other ends thereof extend through opposite transverse slots 120 of the sleeve 112 leading from the slots 114 thereof, whereby said clamping jaws are opened by the outward movement of the shaft 108 and closed by the inward movement thereof. A nut 121 fixed to the reduced end 113 of the head 111 retains said head in the bearing 106. For locking the shaft 108 in its outer or inner positions, a lever 122 pivoted at 123 to a bracket 124 is fixed to the base 28 of the carriage 27, the lower forked end 125 of which engages shoulders of said shaft at 126, and a tension spring 127 extends from said bracket to the upper end of said lever. As the carriages 27 travel outwardly, the arms 110 of the shaft 108 are adapted to engage the upper edge of an inclined bar 128 and the forward and longitudinal edges at 129 of a cam 130 fixed by a bracket 131 to the top of the turn-table 11, thereby giving said shaft and the billet carried by the head thereof a quarter turn before each pass of the billet through the rolls. The bar 128 is pivoted at 132 to the cam 130 and has a lug 133 for engaging same at 134, thereby permitting said bar to be lifted out of the path of the arms 110 of the shaft 108 upon the return movement of the carriage 27 and retained in proper down position when serving as a cam.

Any suitable means may be provided for supporting or holding the billets in proper position to be grabbed by the clamping jaws 116 of the carriages 27 as they are moved outwardly by the operating unit 16. For instance, a platform 135 supported in any suitable manner, and having an outer closed end 136 serving as a stop against longitudinal movement of the billets and therefore causing the clamping jaws 116 to close for gripping the billets due to the pressure against the head 111 from the outward movement of the carriage 27. The billets are therefore grabbed and held by the carriages 27, partially rotated before each pass through the rolls, and after the pass through the last mill, said carriages are moved outwardly at the operating unit 17 and just prior to the end of said movement, the locking lever 122 of the carriage strikes the free end 137 of an arm member 138, which is fixed to the housing of said unit 17 at 139, thereby causing forward or outward movement of the shaft 108 of the carriage and opening the clamping jaws 116 for releasing the finished product.

Operation.—Assuming that the heated billets designated by 140 and from which axles are to be rolled are in place to be grabbed by the carriages 27, that the carriages are held by the pawls 89 at their inner positions, that the clamping jaws 116 are open, that the stops 88 have been set at proper positions, and that the motor 34 has been started, the belt 35 will drive the cross-shaft 31 of the mill 13 by thereby transmitting power through the gear 32 for turning the rolls of said mill. At the same time, the worm-wheel 36 of the cross-shaft 31 transmits power through the worm 37 to the radial shaft 38, which turns clockwise and therefore drives the central bevel gear 42, the sleeve 5 and the push-member 8 counter-clockwise. When one of the arms 9 of the push-member 8 engages the depending pin of the pins 54 carried by the turn-table 11, said push-member exerts pressure against said depending pin and thereby causes the turn-table to rotate one-eighth of a revolution to its next position. Upon said depending pin striking the inclined edge 58 of the cam-ring 60, it rides onto the upper edge thereof out of engagement with the arms of the push-member and permits same to pass thereunder, while the next following pin leaves the upper edge of said cam-ring and becomes the depending pin at the end 62 of said cam-ring. While the turn-table 11 is moving one step, the carriages 27 are moving the same distance and the depending stub-pins or trunnions 64 thereof travel in the space 65 to the radial centers of the next ring sections. At the completion of each step-by-step movement of the turn-table, the cams 104 of the radial shafts 38 and 49 actuate the levers 102 thereby lifting the rods 93 and the pawls 89 and release the rack-bars 80, which being under the tension of the springs 85 are moved outwardly, thereby moving the ring-sections 68 outwardly to the stops 88 and the carriages 27 opposite the operating units 16 and 17 and the mills 13, 14 and 15 to their proper outward positions. As the carriage opposite the operating unit 16 comes to the end of its outward movement, its clamping jaws 116 receive the end of the billet 140 to be carried to the several rolling mills, and due to the pushing pressure of the head 111 thereagainst actuating the lever-arms 117, said clamping jaws grip said billet. At the same time, the cams 81 press the rack-bars 80 into engagement with the gears 32, which force said rack-bars inwardly, thereby returning the carriages opposite the operating units 16 and 17 and mills 13, 14 and 15 to their original positions, the pawls 89 again locking said rack-bars and therefore said carriages against outward movement. The turn-table 11 is now moved to its next position by the next arm 9 of the push-member 8 pressing against the next following depending pin of the pins 54, thus moving the carriages 27 another step, and the described operations are repeated. While the carriages 27 are moving outwardly towards each mill, one of the arms 110 of the shafts 108 thereof by striking the upper edge of the inclined bars 128 and riding up same and engaging the forward and longitudinal edge 129 of the cams 130 give said shafts and the heads 111 thereof a quarter turn and consequently the billets carried by said heads the same turning movements before each pass through the rolls 20 and 21 of the mills. As the carriages 27 move inwardly, the arms 110 lift up the inclined bars 128 and no rotary movements is imparted to the billets. After the carriages 27 move beyond the

last mill still gripping the finished billets, said carriages are moved outwardly by the operating unit 17 and just prior to the end of said movements, the locking levers 122 of the carriages strike the free end 137 of the arm member 138, thereby imparting outward movements to the shafts 108 of the carriages and opening the clamping jaws 116 for releasing the finished billets. After the carriages release the finished billets, they move inwardly, and as the stub-pins or trunnions 64 thereof move in the space 65 of the ring sections 63 by the step-by-step movement of the turn-table, said carriages with their clamping jaws open come again opposite the operating unit 16 for the grabbing of new billets, and all operations described are repeated.

From the drawings and description, it is seen that this machine will automatically grab and feed billets into successive rolling mills; will give the billets a partial turn before each pass; and will automatically discharge the finished product. Also that the timing of the step-by-step rotary movement of the turn-table may be adjustably set and consequently that movement of the carriages and the outward travel of the carriages adjustably limited for the feeding of the billets into each mill the proper distance according to the particular product being rolled.

While I have described the illustrated embodiment of my invention in some particularity, obviously many others will readily occur to those skilled in this art, and I do not, therefore, limit myself to the precise details shown and described, but claim as my invention all embodiments, variations, and modifications thereof coming within the scope of the appended claims.

Having fully described my invention, what I claim is:

1. In a feeding machine for rolling mills, the combination of a turn-table, the turn-table having a plurality of radial-extending slots, a carriage slidably supported in each of said slots, said carriages having means adapted to grip a billet, a plurality of rolling mills arranged around said turn-table, means for rotating said turn-table in a step-by-step movement to bring said carriages opposite successive mills, each of said carriages having a depending trunnion, a ring, the ring having a space for accommodating the travel of said trunnions, said ring being divided into sections for each of said mills, said sections being movable radially, means for moving said sections outwardly to move said carriages in the same direction at each stopping of said carriages opposite said mills, means for moving said sections in the opposite direction to move said carriages in the same direction to their original positions, means for locking said sections and said carriages in their original positions during said rotary movement of said turn-table, and means for releasing said locking means after each said rotary movement of said turn-table and carriages.

2. In a feeding machine for rolling mills, the combination of a turn-table, the turn-table having a plurality of radially extending slots, a carriage slidably supported in each of said slots, said carriages having means adapted to grip a billet, a plurality of rolling mills arranged around said turn-table, means for rotating said turn-table to move said carriages step-by-step opposite said mills, each of said carriages having a depending trunnion, ring sections, the ring sections having spaces for the travel of said trunnions therein, said ring sections being supported

for radial movement, means for locking said ring sections in their inner positions, means for releasing said locking means at the end of said rotary movement of said turn-table, means for moving said ring sections to their outer positions upon being released, means for moving said ring sections to their inner positions after said outer movement thereof and before the next said rotary movement of said turn-table, means for causing said carriages to grip a billet before moving to its position opposite the first mill, and means for causing said carriage to release the billet after moving from its position opposite the last mill.

3. In a feeding machine for rolling mills, the combination of a turn-table, a post, a sleeve rotatable on the post, the turn-table being rotatably mounted on said post and supported by said sleeve, a plurality of rolling mills arranged adjacent the periphery of said turn-table, means for rotating said sleeve, means for causing step-by-step movement of said turn-table from the rotation of said sleeve, said turn-table having a plurality of radially extending slots adapted to register with the vertical centers of said mills, a carriage slidably supported in each of said slots, said carriages having means adapted to grip a billet, means for moving said carriages outwardly at the end of each step-by-step movement of said turn-table, means for moving said carriages inwardly after their outward movements, means for causing said carriages to grip a billet before its outward movement when opposite the first mill, means for causing said carriage to give a partial turn to the billet in its grip on the outward movement when opposite said mills, and means for causing said carriages to release the billet gripped thereby after the inward movement thereof when opposite the last mill.

4. In a feeding machine for rolling mills, the combination of a post, a sleeve rotatable on the post, a turn-table, the turn-table being rotatably mounted on the post and supported by said sleeve, a plurality of rolling mills arranged adjacent the periphery of said turn-table, means for transmitting rotary motion to said sleeve from one of said mills, carriages adapted to grip a billet, the carriages being of greater number than said mills and movable radially on said turn-table for feeding the billets in their grip to said mills, means for moving said carriages outwardly, means for moving said carriages inwardly, and means for causing a stop-and-start movement of said turn-table for moving said carriages successively opposite said mills when said carriages are in their inner radial positions from said rotary movement of said sleeve.

5. In a feeding machine for rolling mills, the combination of a turn-table, a plurality of rolling mills arranged adjacent the periphery of the turn-table, carriages adapted to grip a billet, the carriages being slidably supported by said turn-table and adapted to move radially thereon, means for moving said carriages outwardly, means for moving said carriages inwardly, a post, a sleeve rotatably mounted on the post, a push-member fixed to said sleeve, pins arranged in spaced relation on the arc of a circle and pivotally connected to said turn-table and adapted to be engaged by said push-member for moving said turn-table, and a cam-ring for causing said pins to be engaged successively by said push-member for imparting step-by-step movement to said turn-table to move said carriages opposite said mills.

6. In a feeding machine for rolling mills, the combination of a post, a sleeve rotatable on the post, a turn-table rotatably mounted on said post and supported by said sleeve, a plurality of carriages radially slidable on said turn-table, a plurality of rolling mills arranged adjacent the periphery of said turn-table, means for transmitting rotary movement to said sleeve from the operating power of one of said mills, means for operating said other mills from the rotating movement of said sleeve, means for rotating said turn-table step-by-step from the rotating movement of said sleeve to move said carriages opposite said mills, said carriages having means adapted to grip a billet, means for moving said carriages towards said mills, means for moving said carriages away from said mills, means for locking said carriages prior to each step-by-step movement of said turn-table, and means for actuating said locking means for releasing said carriages at the end of each step-by-step movement of said turntable.

7. In a feeding machine for rolling mills, the combination of a post, a sleeve rotatable on the post, a turn-table rotatably mounted on said post and supported by said sleeve, the turn-table having a plurality of radially extending slots, carriages adapted to grip a billet slidably supported in said slots, a plurality of rolling mills arranged adjacent the periphery of said turn-table, means for transmitting rotary movement to said sleeve from the operating power of one of said mills, means for rotating said turn-table step-by-step from the rotating movement of said sleeve to move said carriages opposite said mills, means for operating said other mills from the rotating movement of said sleeve, each of said carriages having a depending trunnion, ring sections, the ring sections having spaces for the travel of said trunnions therein upon movement of said turn-table, said ring sections being supported for radial movement, means for locking said ring sections in their inner positions prior to each movement of said turn-table, spring means tending to force said sections outwardly, means for releasing said locking means at the end of each movement of said turn-table, to permit outward movement of said sections, means for returning said ring sections to their inner positions, means for causing said carriages to give the billet in their grip a partial turn on their outward movements, and means for causing said carriages to release their grip upon the billet at the end of the next outward movement after the last mill.

8. An article feeding mechanism arranged to feed articles successively to a plurality of separate operating units, which comprises a substantially horizontal support rotatable about a vertical axis, article gripping means above said support, driving mechanism arranged to move the gripping means toward and from an edge of said support, and indexing means moving said gripping means horizontally, the gripping means by its motion toward and from the edge of said support causing the articles to approach and recede from the successive separate operating units.

9. An article feeding mechanism comprising a support having a substantially horizontal plane surface and rotatable about a vertical axis, an article feeding mechanism comprising a shaft carried above said surface and capable of translation in the direction of the shaft axis and of rotation about said axis, article gripping means carried by said shaft, feed means arranged to reciprocate the shaft in the direction of its axis, rotating means arranged to rotate the shaft about its axis, and indexing means moving the axis of the shaft in a plane parallel to the surface of the support.

10. An article feeding mechanism comprising a turn-table support having a substantially horizontal flat surface and rotatable about a vertical axis, an article feeding mechanism comprising a shaft carried above said surface and capable of translation in the direction of the shaft axis and of rotation about said axis, article gripping means carried by said shaft, feed means arranged to reciprocate the shaft in the direction of its axis, rotating means arranged to rotate the shaft about its axis, and indexing means moving the axis of the shaft in a plane parallel to the surface of the support.

11. An article feeding mechanism comprising a turntable having a substantially horizontal plane surface and rotatable about a vertical axis, an article feeding mechanism comprising a shaft carried above said surface, and capable of translation in the direction of the shaft axis and of rotation about said axis, article gripping means carried by said shaft, feed means arranged to reciprocate the shaft in the direction of its axis, rotating means arranged to rotate the shaft about its axis, and means rotating the turn table about its axis.

12. An article feeding mechanism comprising a turntable support having a substantially horizontal flat surface and rotatable about a vertical axis, an article feeding mechanism comprising a shaft carried above said surface substantially radially disposed with respect to said turntable, feed means for moving the shaft toward the periphery of the table and for returning it toward the axis thereof, a plurality of movable jaws carried by the outer end of the shaft, and a snap action mechanism connected to said jaws and arranged to open and close them at the outermost position of the shaft.

13. In combination, a substantially horizontal turntable upon which articles to be worked may be received, a loading platform unit adjacent the turn-table from which articles may be moved in a generally radial direction to said turn-table, a plurality of working units radially arranged with respect to the turn-table, an unloading platform unit also radially positioned with respect to the turn-table, and feed means for moving articles to and from the turn-table, and indexing means moving the turn-table to deliver articles successively to the respective units.

JAMES B. JOHNSON.
